For Inventor
Philip Hise,
By his Attorneys.

C. Snow & Co.

UNITED STATES PATENT OFFICE.

PHILIP HISE, OF CINCINNATI, OHIO.

SADDLER'S KNIFE.

SPECIFICATION forming part of Letters Patent No. 436,479, dated September 16, 1890.

Application filed April 25, 1890. Serial No. 349,549. (No model.)

To all whom it may concern:

Be it known that I, PHILIP HISE, a citizen of the United States, residing at Cincinnati, in the county of Hamilton and State of Ohio, 5 have invented a new and useful Saddler's Knife, of which the following is a specification.

The invention relates to improvements in saddler's knives.

The object of the present invention is to 10 simplify the construction and increase the utility of leather-cutting knives, and enable the cut to be more even and at the expenditure of less pressure than has heretofore been possible.

15 The invention consists in the construction hereinafter fully described, illustrated in the accompanying drawing, and pointed out in the claims hereto appended.

In the drawing, the figure represents a side 20 elevation of a knife constructed in accordance with this invention.

Referring to the accompanying drawing, 1 designates a blade suitably secured to a handle 2, and provided at its front or cutting-edges with a convex portion 4, that extends 25 from one end 5 of the blade beyond the middle and blends with and merges in a reversely curved or concave portion 6, that extends from the convex or outward-curved portion 4 30 to the other end 7 of the blade, and the rear edge 8 of the end 7 of the blade is curved and adapted to elevate the cutting-edge of the knife and prevent the same contacting with and injuring the board while cutting beneath 35 the leather. This construction of end enables the knife to be easily guided through

the leather without injuring the board, and is also a great advantage in tapering or skiving. The knife in cutting is held perpendicular to the leather and is pushed through 40 the same, and the curved edge 8 rests upon the board and the point of the knife is beneath the leather during cutting.

It will readily be seen that the knife is simple and inexpensive in construction, and 45 is adapted to cut evenly with a small amount of pressure and can be readily guided through the leather without liability of injuring the board.

What I claim is—

1. A leather-cutting knife having a blade 1, provided with the outwardly or convexly curved cutting-edge 4 and the inwardly or concavely curved cutting-edge 6, forming a continuation of the edge 4 and providing a 55 point 7, substantially as and for the purpose described.

2. A blade for leather-cutting knives, having the outwardly or convexly curved cutting portion 4 and the inwardly or concavely 60 curved cutting portion 6, forming a continuation of the portion 4 and provided with the curved rear edge 8, substantially as and for the purpose described.

In testimony that I claim the foregoing as 65 my own I have hereto affixed my signature in presence of two witnesses.

PHILIP HISE.
